UNITED STATES PATENT OFFICE.

BERTRAND B. KAHN, OF CINCINNATI, OHIO, ASSIGNOR TO THE ESTATE STOVE COMPANY, OF HAMILTON, OHIO, A CORPORATION OF OHIO.

OVEN CHARGER.

1,416,034.

Specification of Letters Patent. Patented May 16, 1922.

Application filed June 10, 1920. Serial No. 387,978.

To all whom it may concern:

Be it known that I, BERTRAND B. KAHN, a citizen of the United States, residing at Cincinnati, in the county of Hamilton and 5 State of Ohio, have invented certain new and useful Improvements in Oven Chargers, of which the following is a full, clear, concise, and exact description, reference being had to the accompanying drawings, forming a 10 part of this specification.

My invention relates to improvements in oven chargers and is particularly concerned with improvements in oven chargers used for charging muffle furnaces for the burning 15 of vitreous enamel. My invention is not, however, limited in its application to use in connection with muffle furnaces of this type but can also be used for charging other types of ovens, such as tempering, annealing, 20 bake ovens, etc.

The objects of my invention are:

First: to provide a charger comprising means for supporting the work in a horizontal plane during both the charging and 25 withdrawing operations, whereby the work is prevented from shifting its position on the charging device.

Second: to deposit the work upon the supporting tracks during the charging operation 30 and lift it from the supporting tracks during the withdrawing operation by vertical movements.

Third: to provide means whereby the work can be accurately guided to prevent it from 35 brushing against the supporting tracks and muffle walls either during the charging or withdrawing operation.

Fourth: to provide means whereby comparatively large charges may be placed in the 40 oven at one time, and

Fifth: to provide means of the character described which is simple in construction and easy and economical to operate.

Sixth: to provide an oven charger which 45 may be loaded and unloaded properly and quickly by unskilled labor.

Other objects will appear as this description progresses, reference being had to the accompanying drawings in which,

50 Figure 1 is a side elevation of my improved apparatus, certain portions thereof being broken away.

Figure 2 is a longitudinal transverse section taken on line 2—2 of Figure 1.

Figure 3 is a transverse section taken on line 3—3 of Figure 1.

Figure 4 is a vertical transverse section taken on line 4—4 of Figure 1, and

Figure 5 is a vertical longitudinal section taken on line 5—5 of Figure 4.

Throughout the several views, similar reference characters will be used for referring to similar parts.

Heretofore in burning vitreous enamels in muffle furnaces, the work has been charged 65 into the furnace by supporting it on burning points carried by supporting bars, the supporting bars being, in turn, carried by the prongs of a fork. The fork is provided with a handle which is carried on wheels and pivoted adjacent the fork so that by depressing the handle, the fork is elevated and vice versa. In charging the oven with such a fork, the work is placed on the burning points carried by the fork and the handle 70 is then depressed to elevate the fork. The fork is then pushed forwardly on its wheels and into the oven; the handle is then elevated thus permitting the supporting bars to rest upon the supporting tracks of the muffle fur- 75 nace.

In using apparatus of this kind, not only is considerable physical strength required, but the workman must possess considerable skill, otherwise the work may be brushed 85 against the sides of the supporting tracks, and muffle walls either in charging or withdrawing, and spoiled. It will, of course, be understood that the withdrawing operation is carried out in a reverse manner from 90 that of charging, and requires the same amount of strength and skill upon the part of the workman.

Another objection to the apparatus at present in general use for charging muffle 95 furnaces is that in depositing the supporting bars and work from the charging fork onto the supporting tracks and likewise in removing the supporting bars and work from the supporting tracks, the work is held 100 in an inclined position so that the supporting bars do not retain the same position during successive chargings.

The objects of my present invention are, as stated above, to overcome these objections 105 to the apparatus heretofore employed for this purpose.

Referring to the drawings, the reference

characters 10 indicate two I-beams suitably mounted in spaced parallel relation by the U-shaped supporting frames 11. The carriage comprising suitable side members 12, a 5 cross beam 13 and a platform 14 is provided with wheels 15 which roll upon the inner lower flanges 16 of the I-beam 10, the upper inner flanges 17 of the I-beam preventing the tilting of the carriage longitudinally of the 10 tracks. The wheels are provided with flanges 18 for holding the carriage in parallel relation to the tracks. A vertical guide column 20 is supported by the platform 14.

A second carriage comprising the cross 15 beams 21 and the guide plates 22 which are secured to the cross beams 21 as shown in Figures 1, 3 and 5, is mounted to slide upon the vertical guide column 20, the vertical extensions of the guide plates 22 being 20 bolted together in spaced relation by the bolts 23 and 24.

Anti-friction rollers 25, 26, 27 and 28 are secured between the guide plates 22 as shown in Figures 1, and 3 to minimize, as 25 much as possible, the friction between the second carriage and the vertical guide column 20. The two guide plates 22 and the anti-friction rollers 25, 26, 27 and 28 form a guide member for co-acting with the 30 vertical guide column 20 to cause the second carriage to move upwardly and downwardly in a vertical direction as will be described later on. Charging bars 30 have their rear ends secured to the opposite ends 35 of the cross beams 21 by the U-clamps 31, the charging bars thus being held in spaced parallel relation with their front ends projecting beyond the front end of the carriage rolling on the tracks 10. The front ends of 40 the charging bars 30 carry the supporting bars 32 having the burning points 33, the supporting bars and burning points being of the usual construction.

The weight of the work on the supporting bars will tend to tip the upper end of the guide column 20 forwardly. To prevent this, I provide the two guy rods 35, the upper ends of which are secured to the cross plate 36 on the upper end of the guide column 50 20 and the lower ends of which are secured to the rear ends of the flanges 37 projecting from the inner sides of the side members 12 of the carriage traveling on the tracks 10. The upper end of the guide column 20 is 55 provided with laterally extending lugs 40 which co-act with the compression springs 41 to yieldingly limit the upward travel of the carriage mounted on the guide column 20.

60 For elevating the carriage which slides on the guide column 20, I provide a cylinder 45 which is supported by the pedestal 46, the lower end of which is connected with the lugs 47 on the platform 14 (see Figure 4) 65 by means of a pivot pin 48. A piston, not

shown, slides in the cylinder 45 and is connected with the piston rod 50, the upper end of which is pivotally connected with the side plates 22 by the pivot pin 51. With this construction, the cylinder 45 is free to 70 align itself with the piston rod 50, thereby preventing any binding action.

Steam, air, water or other fluid can be supplied to the cylinder 45 in any desired manner, the means which I have illustrated 75 for accomplishing this result comprising a pipe 53, the lower end of which is connected with the end of cylinder 45 and to the upper end of which is connected one end of the flexible conduit 54. The other end of the 80 flexible conduit is connected with the riser 55 which, in turn, is connected with a source of fluid under pressure. The flexible conduit 54 passes over the pulley 56. The take-up sheave 57 carrying a weight 58 rides on 85 the flexible conduit 54 intermediate the pulley 56 and the point of attachment of the flexible conduit 54 to the riser 55.

With the construction above described, when fluid is admitted to the cylinder 45, 90 the piston therein is forced upwardly carrying the side plates 22, the cross beams 21 and the charging bars 30 upwardly. The supply of fluid to the cylinder 45 can be controlled by a valve or any other suitable 95 mechanism located at any desired point.

For moving the carriage back and forth upon the tracks 10, I provide a cylinder 60 which is located beneath the tracks 10 and supported by the two rear frame members 100 11. A piston (not shown) slides in the cylinder 60 and is provided with a piston rod 61 which projects through the front end of the cylinder. The forward end of the piston rod 61 is bifurcated as shown in Figure 2 and two sheaves 62 and 63 are rotatably supported between the bifurcations. Two pulleys 64 rotatably mounted outside of the bifurcations of the piston rod, ride upon the tracks 65 and thus support the outer end of 110 the piston rod. A grooved pulley 66 is rotatably mounted between the front ends of the tracks 10 in alignment with the sheave 63 and a similar grooved pulley 67 is rotatably mounted between the rear ends of the tracks 10 in alignment with the sheave 62. A flexible cable 68 has its intermediate portion trained over the pulleys 66 and 67. The end of the cable which passes over the grooved pulley 66 is then carried backwardly and around the rear side of the sheave 63 and secured to the eye 70 of the tension rod 71, the front end of which is secured to the forward frame member 11. The other end of the cable is brought forward and passed around the sheave 62, then carried rearwardly and secured to the eye 72 of the tension rod 73 which, in turn, is secured to the rear frame member 11. Air, steam or water, under pressure, can be sup- 125 130

plied to the front or rear end of cylinder 60, through the pipes 74 and 75 respectively, it, of course, being understood that the valve or other means for controlling the flow of fluid through these pipes can be located as desired. With the cable disposed over the various sheaves and pulleys as described, the portion of the cable extending between the two grooved pulleys 66 and 67 will move through a distance equal to twice the movement of the piston in the cylinder 60; consequently, to move the carriage from one end of the tracks 10 to the other end requires a cylinder one half the length of these tracks. It will, of course, be clearly understood that by a modified arrangement of the cables, the length of the cylinder could be still further reduced.

In the operation of my improved apparatus, the work is placed upon the burning points 33, the oven door is then opened, fluid is admitted to the cylinder 45 in sufficient quantity to raise the charging bars 30 to a level to bring the bottom edges of the supporting bars 32 above the tops of the supporting tracks in the furnace. Fluid is then admitted to the front end of the cylinder 60 through the pipes 74 whereupon the piston rod 61 is drawn into the cylinder carrying the sheaves 62 and 63 rearwardly and thus causing the upper part of the cable 68 to move forwardly. This portion of the cable is secured to the carriage rolling on the tracks 10 by means of a suitable clamp 80 (see Figure 2.) mounted on the cross beam 13; consequently, the carriage moves forwardly with the cable 68. When the carriage is moved forwardly sufficient to properly place the work with respect to the supporting tracks, the supply of fluid to the cylinder 60 is interrupted and the actuating fluid is then vented from the cylinder 45 through the conduit 54 and riser 55, and a suitable valve (not shown) or in any other desired manner. The carriage slideable on the column 20 thereupon descends, thus permitting the ends of the supporting bars 32 to rest upon the supporting tracks of the furnace. Fluid under pressure is then admitted to the rear end of the cylinder 60 through the pipe 75 and the forward end of the cylinder is vented through the pipe 74. The cable is thereupon actuated to move the carriage rearwardly on the tracks 10 whereby the charging bars 30 are withdrawn from the furnace, the door to which can then be closed.

While I have described the details of the preferred embodiment of my invention, it is to be clearly understood that my invention is not limited to these details nor to the specific use in connection with which I have explained its operation, but is capable of other adaptations and modifications within the scope of the appended claims.

Having thus described my invention, what I claim is:

1. The combination with a track, of a carriage horizontally movable thereon, a vertical guide column mounted on said carriage, a second carriage slidably mounted on said guide column and comprising an elongated guide member having an anti-friction roller at the lower end of its front side and the upper end of its rear side bearing on said guide column, a charging bar secured to said second carriage and projecting beyond the front end of said first-named carriage, means for elevating said second carriage comprising a cylinder supported on said first-named carriage and a piston mounted in said cylinder and connected with the upper end of said elongated guide member, and means for moving said first-named carriage backward and forward on said track comprising a second cylinder located beneath said track, a piston sliding in said second cylinder and having a piston rod projecting from the end thereof, two sheaves carried by the outer end of said piston rod, supporting wheels for the front end of said piston rod, tracks for said supporting wheels, a single sheave at each end of said first-named track, a cable trained over said single sheave, one end of said cable passing over one of the sheaves carried by said piston rod and secured adjacent to the rear end of said track, the other end of said cable passing over the opposite side of said other sheave carried by said piston rod and secured adjacent to the front end of said track and means for securing said first-named carriage to the portion of said cable extending between said single sheaves.

2. The combination with a track, of a carriage horizontally movable thereon, a vertical guide column mounted on said carriage, a second carriage slidably mounted on said guide column and comprising an elongated guide member bearing on said guide column, a charging bar secured to said second carriage and projecting beyond the front end of said first-named carriage, means for elevating said second carriage comprising a cylinder supported on said first-named carriage and a piston mounted in said cylinder and connected with the upper end of said elongated guide member, and means for moving said first-named carriage backward and forward on said track comprising a second cylinder, a piston sliding in said second cylinder and having a piston rod projecting from the end thereof, two sheaves carried by said piston rod, a single sheave at each end of said first-named track, a cable trained over said single sheave, one end of said cable passing over one of the sheaves carried by said piston rod and secured adjacent to the rear end of said track, the other end of said cable pass-

ing over the opposite side of said other sheave carried by said piston rod and secured adjacent to the front end of said track and means for securing said first-named carriage to the portion of said cable extending between said single sheaves.

3. The combination with a track, of a carriage horizontally movable thereon, a vertical guide column mounted on said carriage, a second carriage slidably mounted on said guide column and comprising a guide member bearing on said guide column a charging bar secured to said second carriage and projecting beyond the front end of said first-named carriage, means for elevating said second carriage comprising a cylinder supported on said first-named carriage and a piston mounted in said cylinder and connected with said guide member, and means for moving said first-named carriage backward and forward on said track comprising a second cylinder, a piston sliding in said second cylinder and having a piston rod projecting from the end thereof, sheaves carried by said piston, a cable connected to said first-named carriage and having its ends anchored and intermediate portions passing over said sheaves for moving said first-named carriage backwardly and forwardly over said track.

4. The combination with a track, of a carriage horizontally movable thereon, a vertical guide column mounted on said carriage, a second carriage slidably mounted on said guide column and comprising a guide member bearing on said guide column, a charging bar secured to said second carriage and projecting beyond the front end of said first-named carriage, means for elevating said second carriage comprising a cylinder supported on said first-named carriage and a piston mounted in said cylinder and connected with said guide member, and means for moving said first-named carriage backward and forward on said track comprising a second cylinder, a piston sliding in said second cylinder and having a piston rod projecting from the end thereof and connections between said piston rod and said first-named carriage for moving said first-named carriage in either direction, a distance greater than the distance traveled by said piston.

5. The combination with a track, of a carriage horizontally movable thereon, a vertical guide column mounted on said carriage, a second carriage slidably mounted on said guide column, a charging bar secured to said second carriage and projecting beyond the front end of said first-named carriage, means for elevating said second carriage comprising a cylinder supported on said first-named carriage and a piston mounted in said cylinder and connected with said second-named carriage, and means for moving said first-

named carriage backward and forward on said track comprising a second cylinder, a piston sliding in said second cylinder and having a piston rod projecting from the end thereof, and connections between said piston rod and said first-named carriage for moving said first-named carriage in either direction.

6. The combination with a track, of a carriage horizontally movable thereon, a vertical guide column mounted on said carriage, a second carriage slidably mounted on said guide column, a charging bar secured to said second carriage and projecting beyond the front end of said first-named carriage, means for elevating said second carriage comprising a cylinder supported on said first-named carriage and a piston mounted in said cylinder and connected with said second-named carriage, and means for moving said first-named carriage backward and forward on said track.

7. The combination with a track, of a carriage horizontally movable thereon, means for moving the carriage, a vertical guide column mounted on said carriage, a member slidable on the column, a second carriage secured to said member, a charging bar secured to said second carriage and extending beyond said first carriage, and means for operating said member.

8. The combination with a track, of a carriage horizontally movable thereon, means for moving the carriage, a vertically slidable support mounted on said carriage, a second carriage secured to said support, a charging bar secured to said second carriage and extending beyond said first carriage, and means for operating said support.

9. The combination of a horizontally movable carriage, a vertical guide column mounted on said carriage, a second carriage slidably mounted on said guide column, a charging bar secured to said second carriage and projecting beyond the front end of said first carriage, and means for elevating said second carriage comprising a cylinder supported on said first carriage and a piston mounted in said cylinder and connected with said second carriage.

10. The combination of a horizontally movable carriage, a vertical guide column mounted on said carriage, a member slidable on the column, a second carriage secured to said member, a charging bar secured to said second carriage and extending beyond said first carriage, and means for operating said member.

11. The combination of a horizontally movable carriage, a vertically slidable support mounted on said carriage, a second carriage secured to said support, a charging bar secured to said second carriage and extending beyond said first carriage, and means for operating said support.

12. The combination with a track, of a carriage horizontally movable thereon, means for moving the carriage, a second carriage vertically movable on the first carriage, vertically slidable means mounted on the first carriage for raising and lowering the second carriage, and a charging bar secured to the second carriage and projecting beyond the front end of the first carriage.

13. The combination of a horizontally movable carriage, a second carriage verti-

cally movable on the first carriage, vertically slideable means mounted on the first carriage for raising and lowering the second carriage, and a charging bar secured to the second carriage and projecting beyond the front end of the first carriage. 15

In witness whereof, I hereunto subscribe my name this 28th day of May, 1920.

BERTRAND B. KAHN.
